MOTOR VEHICLE INSTRUMENT PANEL

Gene R. Kiddon, Ann Arbor, Mich., assignor to Ford
Motor Company, Dearborn, Mich., a corporation of
Delaware

Application March 15, 1956, Serial No. 40,637

Term of patent 7 years

(Cl. D14—6)

Fig. 1

FIG.2

FIG.3

Figure 1 is a plan view of a motor vehicle instrument panel showing my new design, the dot and dash portion being shown for illustrative purposes only;

Figure 2 is a perspective view of the motor vehicle instrument panel; and

Figure 3 is a sectional view taken generally along line 3-3 of Figure 2 showing the contour of the motor vehicle instrument panel.

I claim:

The ornamental design for a motor vehicle instrument panel, substantially as shown.
